UNITED STATES PATENT OFFICE

162,691

BRASSIÈRE

William Rosenthal, Bayville, N. Y., assignor to Maiden Form Brassiere Company, Inc.

Application April 17, 1950, Serial No. 9,279

Term of patent 14 years

(Cl. D20—4)

To all whom it may concern:

Be it known that I, William Rosenthal, citizen of the United States, residing at Bayville, Nassau County, New York, have invented a new, original, and ornamental Design for Brassières, of which the following is a specification, reference being had to the accompanying drawing, forming part thereof:

Fig. 1 is a front perspective view of a brassière showing my new design; and

Fig. 2 is a rear perspective view thereof.

I claim:

The ornamental design for a brassière, as shown.

WILLIAM ROSENTHAL.
